UNITED STATES PATENT OFFICE.

ROLLO G. MANNING, OF AMBRIDGE, PENNSYLVANIA.

RAIL CLAMP.

Application filed May 17, 1923. Serial No. 639,589.

To all whom it may concern:

Be it known that I, ROLLO G. MANNING, a citizen of the United States, and resident of Ambridge, in the county of Beaver and State of Pennsylvania, have invented certain new and useful Improvements in Rail Clamps, of which the following is a specification.

This invention relates to rail clamps and more particularly to adjustable rail clamps adapted to line up, clamp, and firmly hold a rail to its support, and has for one of its objects the provision of such a clamp particularly adapted for use in clamping rails supporting turntables, traveling cranes, and the like.

Another object is to provide a clamp of this class that may be securely locked in its adjusted position.

20 A further object is to provide a clamp of this class that will permit very slight adjustments of the rail at right angles to the normal upright position of the rail.

A still further object is to provide a rail clamp having the novel construction, design, and combination of parts hereinafter described.

In the drawings—

Figure 1 is a plan of a rail secured in position by clamps constructed in accordance with my invention.

Figure 2 is a sectional elevation through the rail of Figure 1, showing one of the clamps in elevation and the other in section.

35 Figure 3 is a plan of the eccentric adjusting disk or washer.

Figure 4 is a plan of a slightly modified form of clamp.

Figure 5 is a sectional elevation through a rail having the clamps of Figure 3 applied thereto, the one clamp being in section and the other being in elevation.

Referring more particularly to Figures 1 and 2 of the drawings, the numeral 2 designates a rail adapted to be secured on a supporting plate 3 by the clamps A.

The clamps A comprise a clamping plate 5 which is cut away along its one edge to form an extended flange 6 and shoulder 7, adapted to overlie the top face of, and contact with the edge of the base flange of the rail, respectively. The plate 5 is provided with a centrally arranged circular opening

8 which is enlarged at its upper end as at 9 to form a seat for a washer 10.

The washer 10 is provided with an eccentrically positioned aperture 10^a adapted to receive a bolt 11 which passes through the opening 8 and is secured in the supporting plate 3. The washer 10 also is provided with an aperture 12 for the reception of a suitable wrench or tool used in rotating the washer relative to the clamping plate 5, and to permit the operator to insert his finger or a tool in lifting the washer from its seat.

It will be readily understood that any rotation of the washer 10 relative to the clamping plate 5 will, due to the eccentric mounting of the washer, cause the plate 5 to move toward or away from the rail.

The side wall of the enlarged portion of the opening 8, forming seat 9, has its side walls provided with a plurality or series of semi-circular recesses or notches 14 which extend around its entire circumference, and the washer 10 is provided with three similar recesses or notches 15 which are adapted to cooperate with the notches 14 to form circular openings for the reception of a locking pin 16. The pin 16 is adapted to be inserted in the opening formed by the registering notches 14 and 15 after the washer 10 has been rotated to adjust the rail and forms a positive lock to prevent further movement of the washer relative to the clamping plate.

A suitable covering disk or washer 18 is mounted over the bolt 11 and extends partly over both the clamping plate 5 and the washer 10 and is adapted to cover the opening formed by the cooperating notches 14 and 15.

The bolt 11 is provided with nuts 19 and 20 which are adapted to be tightened down against the washer 18 to secure the several parts together. If, for any reason, the nuts 19 and 20 should become loosened, the rail 2 will not be effected since the locking pin 16 will hold the several parts in their adjusted position.

In Figures 4 and 5 I have shown a slightly modified form of clamp in which the notches 14 are omitted from the walls of the seat portion 9 and a tongue or lug 25 substituted, and in which the three notches 15 in the

washer 10 are replaced with a continuous series of notches 26 extending entirely around its circumference.

In this construction when it is desired to adjust the rail it will be necessary to loosen the nuts 19 and 20 sufficiently to permit the washer 10 to be lifted out of the seat 9 and to then rotate it about the bolt 11 until the desired adjustment is made, when the washer 10 will be again seated with one of the notches 26 registering with the lug 25. It will also be noted that the covering plate or washer 18 is omitted from the modified construction of Figures 4 and 5 since there is no loose locking pin as in the preferred construction and, therefore, the washer 18 is unnecessary.

While I have shown and described two embodiments of my invention, it will be understood that my invention is not limited to these constructions, since various modifications which will readily suggest themselves to those skilled in the art, may be made without departing from the scope of my invention as defined in the appended claims.

I claim—

1. The combination with a rail supporting member, of means for adjustably securing a rail to said member, said means comprising a clamping plate having a circular opening therein, an eccentric washer member mounted in said opening, said clamping plate having its walls surrounding said opening provided with a series of semi-circular notches extending around its entire circumference, and said washer being provided with a plurality of corresponding semi-circular notches adapted to cooperate with the notches in said plate to form circular openings for the reception of a suitable locking pin, a covering disk mounted over said eccentric washer and extending over a portion of said clamping plate, and a bolt passing through said disk, said washer, and said rail supporting member, said bolt being adapted to secure all of said parts together.

2. The combination with a rail supporting member, of means for adjustably securing a rail to said member, said means comprising a clamping plate having a circular opening therein, an eccentric washer member mounted in said opening, said washer being provided with a series of notches, means cooperating with said notches to lock said washer against movement relative to said clamping plate, and a bolt passing through said washer and said plate to secure said parts together and form a pivotal mounting for said washer.

3. The combination with a rail supporting member, of means for adjustably securing a rail to said member, said means comprising a clamping plate having a circular opening therein, an eccentric washer

member mounted in said opening, said washer being provided with a series of notches, means cooperating with said notches to lock said washer against movement relative to said clamping plate, said washer being provided with a tool receiving aperture adapted to receive a tool to facilitate the adjustment of said washer, and a bolt passing through said washer and said plate to secure said parts together and form a pivotal mounting for said washer.

4. Means for adjustably securing rails to a supporting member comprising a clamping plate adapted to engage the edge and overlie the base flange of a rail, said plate being provided with a circular opening therein, an eccentric washer mounted in said opening, a bolt passing through said washer, said plate and said supporting member to secure the several parts together and form a pivotal mounting for said washer, and means for locking said washer against movement relative to said clamping plate.

5. Means for adjustably securing rails to a supporting member comprising a clamping plate adapted to engage the edge and overlie the base flange of a rail, said plate being provided with a circular opening therein, an eccentric washer mounted in said opening, a bolt passing through said washer, said plate and said supporting member to secure the several parts together and form a pivotal mounting for said washer, means for locking said washer against movement relative to said clamping plate, and a covering disk mounted on said bolt and adapted to overlie said washer and said clamping plate to prevent accidental dislodgment of said locking means.

6. Means for adjustably securing rails to a supporting member comprising a clamping plate adapted to engage the edge and overlie the base flange of a rail, said plate being provided with a circular opening therein, an eccentric washer mounted in said opening, a bolt passing through said washer, said plate and said supporting member to secure the several parts together and form a pivotal mounting for said washer, a plurality of cooperating notches formed in said washer and said clamping plate, and a locking pin adapted to be inserted in the aperture formed by the registering ones of said notches to lock said washer against movement relative to said clamping plate.

7. Means for adjustably securing rails to a supporting member comprising a clamping plate adapted to engage the edge and overlie the base flange of a rail, said plate being provided with a circular opening therein, an eccentric washer mounted in said opening, a bolt passing through said washer, said plate and said supporting member to secure the several parts together and form a pivotal mounting for said washer,

a plurality of cooperating notches formed in said washer and said clamping plate, a locking pin adapted to be inserted in the aperture formed by the registering ones of said notches to lock said washer against movement relative to said clamping plate, and a covering disk mounted on said bolt

and adapted to overlie said washer and said clamping plate to prevent accidental dislodgment of said locking means.

In testimony whereof I have hereunto signed my name.

ROLLO G. MANNING.
